UNITED STATES PATENT OFFICE.

MIKE SARBIJ, OF LUDLOW, MASSACHUSETTS.

DOOR-LOCK.

1,378,622.

Specification of Letters Patent. Patented May 17, 1921.

Application filed July 27, 1920. Serial No. 399,234.

To all whom it may concern:

Be it known that I, MIKE SARBIJ, a citizen of Ukraine, residing at Ludlow, in the county of Hampden and State of Massachusetts, have invented certain new and useful Improvements in Door-Locks, of which the following is a specification.

The present invention relates to certain new and useful improvements in door locks and particularly to that class of lock that employs a manually shiftable locking bolt, operable only from one side of the door with means for retaining the locking bolt in its operative and inoperative positions.

15 With the above and other objects in view, the present invention consists in the novel form, combination and arrangement of parts hereinafter more fully described and shown in the accompanying drawings, wherein like reference characters indicate similar parts throughout the several views.

In the drawings,

Figure 1 is a fragmentary front elevational view of a portion of a door and jamb 25 with the present form of lock built therein,

Fig. 2 is a vertical sectional view taken on line II—II of Fig. 1,

Fig. 3 is a vertical sectional view taken on line III—III of Fig. 2 showing the lock bolt 30 projected and retained in locked position,

Fig. 4 is a horizontal sectional view taken on line IV—IV of Fig. 3 showing the star wheel engaging the rack portion of the bolt for shifting the same,

Fig. 5 is a detail fragmentary view, partly in section showing the locking bolt in retracted inoperative position, and

Fig. 6 is a perspective view of the locking bolt, removed from the casing.

40 Briefly described, the present invention has for its primary object to provide a lock for doors and the like, wherein the bolt is manually shiftable in opposite directions and operable from one side of the door. The 45 bolt is slidably mounted in a casing provided in the door and has the nose portion thereof projected into a keeper provided in the door jamb. One face of the bolt is provided with teeth and is adapted to be engaged by a gear or star wheel for shifting the bolt to its operative and inoperative positions. A latch device operable from within the door positively holds the bolt in either of its positions.

55 Referring more in detail to the accompanying drawings, there is illustrated a por-

tion of a door indicated by the reference character 1 and a portion of a door jamb indicated by the reference character 2. The edge of the door jamb 2 is provided with a 60 bolt keeper opening 3 with a face plate 4 countersunk in the edge of the jamb and having an opening therein registering with the socket 3.

A lock mechanism is carried by the door 1 65 and includes a casing positioned within an opening in the door and formed of side walls 5, a detachable rear wall 6, a bottom wall 7 and a forward wall 8 that lies flush with the edge of the door 1 and has an opening 9 70 therein that registers with the keeper socket 3 in the top jamb 2. The form of bolt employed in the lock is shown in detail in Figs. 2 and 6, as being substantially H-shaped in cross section defining opposite spaced flanges 75 10, a forward reduced nose 11 and a series of teeth 12 upon the upper face thereof. The opposed faces of the side walls 5 of the lock are provided with guides 13 extending between the flanges 10 on each side of the bolt 80 to provide a guide for the sliding movements of the bolt. The means for manually shifting the bolt includes a stub shaft 14 rectangular in cross section and inserted through aligned openings 15 and 16 in the 85 door 1 at opposite sides of the lock casing and retained therein by the screw plug 17 as shown in Fig. 2. A gear or star wheel 18 is carried by a hub 19 having a rectangular bore through which the rectangular shaft 14 90 projects while the inner projecting end of the shaft 14 is provided with an operating knob 20.

In order to maintain the bolt 11 in either its operative or inoperative position, a latch 95 device is associated therewith and includes a pin 21 slidably projecting through the tubular housing 22 carried by the bottom wall 7 of the casing and having a disk 23 fixed thereon and engaged by a coil spring 100 24 surrounding the pin within the housing 22 to project the pin upwardly while a cut-out portion 25 is formed in the inner face of the door 1 to provide a clearance space for the lower handle end 26 of the pin 21. 105 As shown in Figs. 2, 3, and 5, the lower face of the bolt 11 is provided with a lug 27 for engagement by the pin 21. The lug 27 is of elongated form having straight end walls and a curved bottom wall 27' to permit the end of the pin 21 freely to ride thereover when removed from engagement with 110

either end wall when the bolt 10 is shifted in either direction, this construction permitting the finger grip 26 being released while the spring 24 maintains the pin in engagement with the lug to insure the locking position thereof when the lug is moved to a position to present either end wall thereof laterally of the pin.

In the operation of the device, the lock 10 being operable only from one side of the door, the handle 26 is grasped to lower the pin 21 against the tension of the spring 24 and to remove the pin from engagement with the end wall of the bolt lug 27. When 15 so positioned, rotation of the knob 20 in either direction will cause a reciprocation of the bolt 9 by the star wheel 18 upon the shaft 14 engaging the rack face 12 of the bolt. The latch pin 21 riding over the 20 curved lower wall of the lug is forced by the spring 24 to move upwardly for engagement with either end wall of the lug 27, the pin engaging the lug as illustrated in Fig. 3 to hold the bolt in its locked position, while in Fig. 5, the bolt is illustrated as retained in its retracted inoperative position. This form of lock may be 25 alone employed as a retaining means for a door or similar structure, or the device may 30 be employed as a night latch attachment for a door or the like provided with the usual tensioned latch bolt.

While there is herein shown and described the preferred embodiment of the invention, it is nevertheless to be understood that minor 35 changes may be made therein without departing from the spirit and scope of the invention.

What is claimed as new is:—

1. A lock of the type described comprising 40 a casing, a bolt slidable therein, teeth formed upon one side of the bolt, a gear wheel engaging said teeth for shifting the bolt, means for holding the bolt in its operative and inoperative positions, said means 45 comprising a tensioned pin carried by the lock casing and an elongated lug having a curved bottom face carried by the bolt adapted to be engaged by the pin.

2. A lock of the type described comprising 50 a casing, a bolt slidable therein, teeth formed upon one side of the bolt, a gear wheel engaging said teeth for shifting the bolt, means for holding the bolt in its operative and inoperative positions, said means 55 comprising a tensioned pin slidably projecting through the bottom wall of the lock casing, an operating handle for said pin, a lug carried by the underside of said bolt and adapted to be engaged by said pin for holding the bolt in its operative and inoperative positions.

In testimony whereof I affix my signature.
MIKE SARBIJ.
